UNITED STATES PATENT OFFICE.

TILGHMAN F. LIPPENGOOD, OF LIBERTYVILLE, IOWA.

METAL-SHEARS.

SPECIFICATION forming part of Letters Patent No. 731,312, dated June 16, 1903.

Application filed November 15, 1902. Serial No. 181,508. (No model.)

To all whom it may concern:

Be it known that I, TILGHMAN F. LIPPENGOOD, of Libertyville, in the county of Jefferson and State of Iowa, have invented a new 5 and useful Improvement in Metal-Shears, of which the following is a specification.

The object of my invention is to provide a simple and convenient metal-shears adapted to be used either by hand or by power and 10 which may be easily changed from right to left hand cutting and which by having two cutting edges for the movable blade shall be capable of running for a long time without regrinding.

15 It consists in the novel construction and arrangement of parts which I will now proceed to describe with reference to the drawings, in which—

Figure 1 is an end view; Fig. 2, a plan view; 20 Fig. 3, a side view, partly in section, on the line 3-3 of Fig. 1; and Fig. 4 is a sectional detail on line 4-4 of Fig. 3.

In the drawings, A represents the upper and B the lower jaw of a stationary rigid 25 framework. The upper jaw is rigidly connected to an overhanging arm C, which extends horizontally from a vertical frame-plate D, and which frame-plate is rigidly connected to a horizontal table-surface E, which 30 at its outer edge immediately beneath the upper jaw carries the lower jaw B. On these two jaws are carried the two knives that form the cutting portions of the shears. The upper knife K is movable and the lower knife K' is relatively stationary. The lower knife 35 K' occupies a vertical plane, is slotted at a, and connected adjustably to the side of the lower jaw of the frame by bolts a'. The upper knife is arranged in a vertical plane immediately adjacent to the upper or cutting 40 edge of the lower knife and is constructed and arranged to oscillate about an axial center. This knife is made with a double cutting edge, one along its upper side and the other along its lower side, and its axial center is arranged to be shifted from one end of the knife and one side of the machine to the other end of the knife and the other side of the machine, so as to adapt it for either right 45 or left hand cutting. For this purpose it has two pivotal holes b and b', one at each end,

and midway between these holes and in longitudinal position in the knife is an elongated slot b². Through one or the other of the end holes b or b' there is secured a pivot-bolt c, 55 which connects the knife-blade to the upper jaw, and through the slot in the middle of the knife there projects a crank-pin d from a rotating disk F. This crank-pin has around it an antifriction-roller, which bears against the 60 sides of the slot and forms a roller-bearing to reduce friction. The revolving disk F is fast upon the end of a horizontal shaft G, that rotates in bearings in the upper jaw and opposite frame-plate and carries on the end opposite the disk a gear-wheel H. This gear-wheel is in mesh with another one, H', which is fast on a short crank-shaft H², having a hand-crank H³ for turning it and having a bearing 65 in an offsetting bracket H⁴. For turning the 70 shaft G by power a band-pulley H⁵, having a small gear-wheel H⁶ attached, transmits its power through an idler H⁷ to the gear of the shaft G.

Outside of the jaws A B of the main frame 75 there is supported a horizontal shelf T, which has flanged plates t bent down and slotted and fastened by bolts t' to the lower jaw, so as to be vertically adjustable. This shelf is about at the level of the junction of the two 80 knives, and it serves to support the sheet metal to be cut. To hold the sheet metal up to the knives as it is fed along, there are two rollers r r set on the shelf-surface in a slanting or oblique position, so as to feed slightly 85 forward toward the knives as the metal plate is pushed along the shelf.

Inside the knives there is formed the table-surface E, which receives the sheet of metal cut off. On this table-surface is a movable 90 gage-flange R, connected adjustably by set-screws s to the edges of the table E, so as to be adjusted closer to or farther from the knives to determine the width of the cut. Beside this table E and fixed to the upper surface of the lower jaw B of the framework there is a flat bow-spring S, which lies beneath the upper knife and is pressed down by the same when the knife descends. This serves to lift the severed sheet of metal when 95 the knife rises.

It will be seen that my upper knife is double-

edged and symmetrically constructed at each end, so as to allow the pivot-pin of the knife to be shifted to the opposite side of the wrist-pin on the disk, for which purpose the knife-blade is simply turned over and the pivot-pin is put through the opposite end of the knife and into a corresponding hole in the upper jaw of the main frame. This converts the machine for a right-hand shears to a left-hand shears, and vice versa.

I is a guard and guide-plate, fastened to the top of the upper jaw and overlapping the movable knife to act as a guide for the same and hold it in its true plane of action.

Having thus described my invention, what I claim as new, and desire to secure by Letters Patent, is—

1. A shears comprising a stationary knife and a movable knife, the movable knife being formed with two opposite cutting edges and a pivotal bearing at each end to render

the same reversible, and means for oscillating the movable knife substantially as described.

2. A shears comprising a stationary knife and a movable knife, the movable knife being formed with two opposite cutting edges, and having a pivotal bearing at each end, and a longitudinal slot in the middle, a driving-shaft with crank-pin playing in said slot, and means for rotating said shaft substantially as described.

3. A shears comprising two knives arranged in a vertical frame, and a horizontally-projecting shelf arranged beside the knives and having on its upper surfaces oblique or diagonally-arranged rollers extending across the width of the shelf substantially as and for the purpose described.

TILGHMAN F. LIPPENGOOD.
